(57) **CLAIM**

The ornamental design for shutter, as shown and described.

DESCRIPTION

FIG. 1 is a front elevational view in accordance with my new design, a rear elevational view being identical;

FIG. 2 is a greatly enlarged cross-sectional view of a portion of FIG. 1 taken along line 2—2 of FIG. 1;

FIG. 3 is a greatly enlarged cross-sectional view of a portion of FIG. 1 taken along line 3—3 of FIG. 1;

FIG. 4 is a top perspective view of the frame of the shutter shown in FIG. 1;

FIG. 5 is an enlarged exploded partial perspective view of a corner assembly of the shutter shown in FIG. 1; and,

FIG. 6 is a greatly enlarged exploded partial perspective view of the corner assembly shown in FIG. 5.

The broken lines are for illustrative purposes only and form no part of the claimed design.
